UNITED STATES PATENT OFFICE.

HENRY LOBDELL, OF TROY, NEW YORK.

CURTAIN-STICK.

SPECIFICATION forming part of Letters Patent No. 292,284, dated January 22, 1884.

Application filed November 22, 1883. (No model.)

To all whom it may concern:

Be it known that I, HENRY LOBDELL, a resident of the city of Troy, in the county of Rensselaer and State of New York, have invented 5 certain new and useful Improvements in Curtain-Sticks; and I do hereby declare that the following is a full, clear, and exact description of the invention, that will enable others skilled in the art to which it appertains to make 10 and use the same, reference being had to the accompanying drawings, and to the letters of reference marked thereon, which form a part of this specification.

Similar letters refer to similar parts in the 15 several figures therein.

My invention relates to improvements in curtain-sticks and the method of attaching curtains thereto; and it consists in providing the stick with a row of curtain-fasteners having 20 pointed hooks adapted to pierce the curtain and secure the same to the stick, the latter being properly prepared to receive the hooks and curtains.

The object of my invention is to facilitate 25 the proper adjustment and readjustment of a curtain upon a stick for use as a curtain.

Figure 1 is a perspective view of a portion 30 of a curtain and stick, showing my improved method and hooks. Fig. 2 is a cross-section taken at the broken line *a b* in Fig. 1. Fig. 3 is a cross-section taken at the broken line *c d* in Fig. 1. Fig. 4 is a cross-section taken at the broken line *e g* in Fig. 1. Fig. 5 is a side elevation of one of the hook-tacks.

35 By the term "curtain-sticks" I intend to include curtain rollers, poles, and slats.

The difficulties experienced in attaching curtains to their rollers by means of common tacks are well known, and I have ascertained that 40 by employing hook-headed tacks *C* many of these difficulties are overcome. I prefer to first insert the pointed end *P* in the stick, ranging the tacks at proper intervals in a straight line to form a row of tacks extending 45 longitudinally of the stick, with the hooks all projecting in the same direction, and transversely of the roller, as shown in Figs. 2 and 4. I then place one corner edge of the curtain end to be attached to the stick beneath the 50 hook at one end of the row of tacks, in the position shown in Fig. 2, and drive the tack

into the stick until the hook penetrates the curtain, as shown in Fig. 3; then grasp the curtain at the opposite side on the same end and draw it taut, and hold it in such a position that the end edge will rest just under the hooks of the remaining tacks, as shown; then drive the remaining tacks in the same manner as the first. The hook-tacks may be partially inserted at the factory when the stick 60 is manufactured, ready for use as I have described. In this manner the curtain can be easily, properly, and quickly adjusted, as it is not necessary to pick up each tack separately and adjust the same in the proper position while the curtain is also being adjusted to its proper position, as is necessary in the use of the common flat-headed tack. When my hook-tacks are adjusted in a straight line, forming a row extending longitudinally of the stick, 70 they form a guide for properly adjusting the curtain. Flat-headed tacks cannot be so adjusted, because their points must pierce the curtain before entering the stick.

The hook may be circular in shape, as shown 75 in Fig. 4, or of any other desired shape, which presents two points—one to pierce and secure the tack to the stick, and one to pierce and secure the curtain.

There may be a slot, *D*, cut in the stick transversely of the same, which will permit the hook to be countersunk therein, to present a comparatively smooth and even outer surface.

What I claim as new, and desire to secure 85 by Letters Patent, is—

1. A curtain-stick provided with a row of curtain-fasteners ranged longitudinally of the stick, said fasteners having pointed hooks adapted to pierce and secure the curtain upon the stick, substantially as described, and for 90 the purposes set forth.

2. A hook-headed tack, in combination with a transversely-slotted curtain-stick and curtain, substantially as described, and for the 95 purposes set forth.

In testimony whereof I have hereunto set my hand this 19th day of November, 1883.

HENRY LOBDELL.
